UNITED STATES PATENT OFFICE

AUGUST H. KOHLMAYER AND FREDERICK A. KOHLMAYER, OF DETROIT, MICHIGAN

THERMOSTATIC OVEN CONTROL MECHANISM

Application filed January 23, 1928, Serial No. 248,588. Renewed December 9, 1930.

This invention relates to the ovens of gas stoves, and particularly to mechanisms for controlling in common the ventilation of such ovens and the delivery of gas to the burners thereof.

An object of the present invention is to exercise automatic control over an oven-venting damper and a valve in the pipe delivering fuel to the burner of the oven by

10 mechanism responding to a single thermostatic means.

Another object is to provide for the facile adjustment of such a mechanism to regulate the temperature at which it takes effect.

15 Still another object is to reduce a thermostatic oven control mechanism of the described character to a maximum simplicity, to thereby minimize the original cost and the expense of upkeep.

20 These and various other objects the invention attains by the construction herein-after described and illustrated in the accompanying drawings, wherein:

Figure 1 is a front view of an oven equipped with the improved control mechanism.

Figure 2 is a vertical sectional view of the same taken upon the line 2-2 of Figure 1.

Figure 3 is a horizontal sectional view of 30 said oven taken upon the line 3-3 of Figure 2.

Figure 4 is a rear view of the oven.

Figure 5 is an axial sectional view of a 35 valve adapted to be thermostatically controlled.

Figure 6 is a detail elevational view of the thermostatic control member.

In these views, the reference character 1 designates an oven which may or may not 40 constitute an integral portion of a gas range. Preferably said oven is provided with hollow walls filled with some suitable heat insulation such as is indicated at 2. Access is had to the oven by the usual hinged door 3 at the front thereof, said door being normally held closed by a suitable latch 4 as is 45 common practice. It is preferred to dispose in the lower portion of said oven a perforated false bottom 5 between which and the true 50 bottom of the oven, one or more burners 6

are mounted. In order that the heated air and gases rising from said burners in the usual manner may be distributed with substantial uniformity within the oven proper, it is preferred to slightly space a pair of plates 6^a from the side walls of the oven and to perforate said plates for the discharge into the oven of the gases rising between said plates and side walls.

To the burners 6 is connected a gas delivery pipe 7 and the delivery of gas through said pipe is adapted to be controlled by the usual manually operable valve 8.

At the rear of the oven 1 the pipe 7 has an upwardly arched portion in which is provided a valve 9 (see Figure 5) adapted to regulate the flow of fuel responsive to only a slight effort. As will presently appear, this valve is under thermostatic control.

Beneath each burner 6 there is formed in the oven bottom one or more openings 10 through which air may be supplied to the burners 6 to support combustion. Preferably baffle plates 11 are secured to the oven slightly below the openings 10 to minimize the downward radiation of heat from the burners.

In the rear wall of the oven, and preferably in the center portion of said wall, there is formed an outlet 12 for air and gases, the necessary circulation through the oven being thus established jointly by the openings 10 and 12. Such ventilation is regulable by a damper 13 controlling the opening 12 and hinged to the oven, preferably exteriorly thereof.

Describing now a mechanism for thermostatically controlling the valve 9 and damper 13 in common, 14 designates a thermostat disposed within the oven preferably in the top portion thereof, since the maximum temperatures are encountered in said portion. While said thermostat may be of various forms, it is preferred to form this device of a bi-metallic sheet metal plate, utilizing differential co-efficients of expansion of its component metals to cause it to flex proportionately to the temperature to which it is exposed. One end of said thermostat is hinged upon a bracket 15 carried by the rear wall

of the oven and its other end is engaged by a rod 16 which passes through a front wall of the oven and carries an actuating crank 17 externally adjacent to said wall. The forward end portion of the rod 16 is threaded into a feed nut 18 rigidly secured in any suitable manner to the front wall of the oven and preferably set into said wall. In order to permit a free swinging of the thermostatic plate 14 about its hinged end responsive to longitudinal adjustment of the rod 16, it is preferred to thread the rear end portion of said rod and to engage its threads by a pair of nuts 19, one at each side of the plate 14, having their opposing faces spherically rounded to permit the desired play between said rod and plate. Also the opening 20 formed in said member to receive the rod 16 is slightly elongated to permit of the necessary flexure 20 of said member.

The mechanism actuatable by the thermostat 14 comprises a bell crank 20 exteriorly pivoted upon the rear wall of the oven and elongated substantially vertically. The actuating connection from the thermostat to said bell crank is established by a pin 21 freely slideable in an opening 22 in the rear oven wall, and engageable at its front end with the mid portion of the plate 14. An abutment 30 engageable by said pin is carried by a screw 24 threaded in the upper end of the lever 20 and is adjustable to and from said pin. A link 26 establishes a swinging connection between the lower end of the lever 20 and the damper 13, and it is preferred to provide said link with a series of longitudinally spaced openings (see Figure 2) to permit its connection to said lever at various points of its length to thereby regulate the degree of 40 opening of the damper 13.

To control the valve 9 by the lever 20, the stem 9^a of said valve carries at its forward end an abutment 27 adapted to bear against and be actuated by the lever to close said 45 valve. The open position of the valve is normally established by a spring 28 coiled upon the stem 9^a between the casing of said valve and said abutment. A leather diaphragm 29 in said casing establishes a seal against leakage of gas.

In the operation of the described mechanism, when the temperature within the oven rises beyond a predetermined point, the resulting flexure of the member 14 acts through 55 the pin 21 upon the bell crank 20 to rock the upper end thereof rearwardly so that the consequent forward actuation of the lower portion of said lever tends to close the damper 13. The described actuation of the bell crank 60 further acts through the stem 9^a and abutment 27 to shift the valve 9 toward its seat. Thus the flow of gas to the burners is reduced and the oven temperature is maintained at the desired minimum.

65 It is to be understood that the actuation

of the valve 9 will in no event be sufficient to fully cut off the delivery of gas to the burner. If that were permitted, the subsequent opening of the valve by the spring 28 would result in escaping gas.

70

When the construction is originally tested, the screw 23 is adjusted to assure a response of the lever 20 to deflection of the thermostat through a suitable range. The user of the oven, however, may more definitely regulate 75 the thermostatic mechanism by turning the crank 18 and thus feeding the rod 16 forwardly and rearwardly to swing the thermostatic member 14 correspondingly. Preferably a suitable arcuate dial piece 30 is associated with said crank and on said dial piece is indicated by radial markings a series of temperatures which may be maintained in corresponding positions of adjustment of the crank 17.

80

85

90

Said mechanism is of a relatively simple nature, largely because of the use of a single thermostat to exercise both of the desired functions of fuel control and ventilation control. Because of its simplicity and the fewness of its parts, the mechanism is relatively inexpensive and is not likely to get out of order.

95

While it will be apparent that the illustrated embodiment of our invention herein disclosed is well calculated to adequately fulfill the objects and advantages primarily stated, it is to be understood that the invention is susceptible to variation, modification and change within the spirit and scope of the 10 subjoined claims.

What we claim is:

1. In a thermostatic control mechanism, the combination with an oven having openings for the admission and discharge of air, of a burner for heating said oven, means for delivering fuel to said burner, a damper controlling one of said openings and a valve arranged exteriorly of the oven controlling said fuel delivery, a lever pivoted between its ends upon the oven exteriorly thereof, an actuating connection from said lever at one side of its pivot to said damper, an actuating connection from said lever at the other side of its pivot to said valve, a thermostat within the oven subjected to the heat thereof, and a pin slideable in a wall of the oven transmitting control from said thermostat to said lever.

115

2. In a thermostatic control mechanism, the combination with an oven having a vent opening in a wall thereof, of a lever member exteriorly pivoted upon said wall, a damper controlling said opening, means for actuating said damper from one end of said lever, a thermostat within the oven subjected to the heat thereof, and a pin slideable in a wall of the oven forming an actuating connection to said lever from said thermostat.

120

3. In a thermostatic control mechanism, the combination with an oven and a heater for 130

125

said oven, said oven having a vent opening, a damper controlling said opening, a device controlling energization of said heater, a thermostat within the oven, a lever exteriorly pivoted upon the oven, means for actuating said lever by said thermostat, and direct actuating connections from said lever to said damper and control device.

4. In a thermostatic control mechanism,
10 the combination with an oven having an air vent opening in a wall thereof, of a closure for said opening, a burner for heating said oven, a valve exteriorly adjacent to said wall controlling delivery of fuel to said burner, a lever pivoted upon said wall, a direct actuating connection to said closure from one end of said lever, a thermostat within said oven, means operating through said wall adapted to actuate the other end of said lever from
15 said thermostat, and means carried by said lever between its ends exercising control of said valve.

In witness whereof we hereunto set our hands.

25 AUGUST H. KOHLMAYER.
FREDERICK A. KOHLMAYER.
